UNITED STATES PATENT OFFICE.

JOHN A. HEBB, OF HOPWOOD, AND WILLIAM J. McDADE, OF UNIONTOWN, PENNSYLVANIA.

MINE CAR.

Original application filed November 6, 1919, Serial No. 336,025. Divided and this application filed October 6, 1920. Serial No. 415,066.

To all whom it may concern:

Be it known that JOHN A. HEBB and WILLIAM J. McDADE, citizens of the United States, residing at Hopwood and Union-

town, respectively, in the county of Fayette and State of Pennsylvania, have invented certain new and useful Improvements in Mine Cars, of which the following is a specification.

10 Our invention consists of an improvement in mine cars, and particularly in the braking mechanism therefor. It has in view to provide means for braking the car from either end so as to avoid the necessity of standing on the front end of a car with the attendant risks. Ordinarily, mine car brakes are operated through levers, cranks, and rigid pitmen, so that if a braking lever is mounted at either end of a car and connected with the brake shoe mechanism, operation of either lever will transmit undesired movement to the other, resulting in jamming or straining of the parts, or the necessity of releasing before action. Our invention obviates all such objections, and renders it possible to operate the brakes from either end without disturbing the operative lever at the other end.

We have shown the operating levers at each end portion of the car, at divergently opposite side portions thereof, connected to cross rock shafts adapted to transmit the braking pressure through the connected mechanism hereinafter described. We also show a modified arrangement of levers, one at the side near the end of the car, and the other arranged across the opposite end, and each connected to common actuating mechanism.

40 The present invention is a division of the subject matter of our prior application Serial No. 336,025 filed November 6, 1919.

In the drawings, illustrating preferred embodiments of the invention:

45 Fig. 1 is a side view in elevation of a mine car provided with our improvement;

Fig. 2 is an end view of the same;

Fig. 3 is a perspective detail view showing the actuating connection between the 50 lever and rock shaft;

Fig. 4 is a similar view showing a modified arrangement utilizing a side lever and an end lever at opposite end portions of the car.

Referring to the drawings, 2^a is the body of the car of usual design, mounted on wheels 3^a and provided with a brake shoe 4^a at each side, of well known form. Said shoes are mounted for vertical adjustment towards and from the wheels 3^a by a bolt 5^a and a connected lever 6^a of a rock shaft 7^a. The rock shaft is mounted in suitable bearings 8^a along the sides of the car, and each rock shaft has at each end a lever arm 9^a for operation together by either one of two main levers 10^a and the interposed mechanism shown. Car 2^a is of the end dumping type, for which reason the levers 10^a are located at the diagonally opposite sides of the car, one near each end and within reach of an operator standing on the end platform. Each lever 10^a is connected to a cross rock shaft 15^a extending across under the car at each end, in bearings 16^a and has a lever arm 13^{aa} similar to arm 13^a. Each arm is connected by chain 14^a to arm 9^a of the rock shaft at each side of the car, so that operation of either lever 10^a will simultaneously exert tension on the chains and actuate both rock shafts 7^a to depress the 80 brake shoes to engage the wheels. Levers 10^a are mounted in guards 12^a, and suitable ratchet or other type of holding mechanism may be employed therewith, if desired.

In the drawings, both the levers 10^a are shown in released position. In order to set the brake, the operator has only to pull the lever 10^a nearest him toward the end of the car. This will rock cranks 13^a and 13^{aa} downwardly, pulling down on the flexible 90 connections on chains 14^a, moving cranks 9^a on shafts 7^a in a corresponding direction. Such movement of cranks 9^a rocks shafts 7^a in a direction to force bolts 5^a downward, thereby causing shoes 4^a to engage the 95 wheels. Once a lever 10^a is so moved, it may be held in set position by teeth on members 12^a until released.

By reason of the flexible connections 14^a, movement of one lever 10^a will not effect 100

the movement of the other one. This has a definite advantage in that it requires the brake to be released from the same end at which it is set, and enables the levers 10^a at each end to be independently moved to locked position.

The value of this feature may be readily appreciated. The cars travel back and forth without being turned around. The 10^a miner or operator may always ride on the rear end of the car relatively to the direction of travel of the car, and have a brake accessible to him. If now the car is stopped at on a grade, the miner will set the brake at 15 the end on which he is riding, that being most convenient. When the miner gets on the car, to travel in the opposite direction, he will get on at the other end. He can, before getting on, set the brake from the 20 end on which he will ride, and then go to the front of the car and release the brake first set. After releasing the brake first set, the car cannot move until the operator gets back on to the rear and also moves the rear 25 handle to released position. There is, accordingly, no necessity for him to be taken by surprise and forced to hop onto a moving car, or to let a car get away from him.

Furthermore, he is not in danger, when 30 stopping the car, of having the front lever catch when he attempts to operate the rear brake, as the movement of one handle does not move the other. Neither is there any necessity for winding up several inches of 35 slack chain when setting the brakes before the brakes start to move, which is the case with some car brakes employing chains.

In Fig. 4 we show a modified construction 40 in which the construction just described is used at one end of the car, with a side lever 10^a, and the rock shafts 7^a are connected by lever arms 9 and chains 14 with the arm 13 of lever 10, pivoted at 11 to the front of a car, as disclosed in the first application 45 above referred to. This arrangement is of advantage with a car having one end gate only or with a combined end gate and dumping bottom car, as will be readily understood.

With either construction the operator may 50 apply braking power to the wheels while standing at the rear of the car, with perfect safety and ample power, equally distributed throughout the several wheels.

The construction is very simple, cheap, 55 and effective, and provides a safe, powerful, and direct acting equipment. It may be applied to other than mine cars and may be changed or varied from in different details by the skilled mechanic, but all such changes are to be considered as within the scope of the following claims.

What we claim is:

1. The combination with a mine car hav-

ing wheels thereon, of a braking mechanism 65 therefor, said mechanism comprising a vertically movable shoe adapted to be moved into and out of wheel engaging position, a shaft extending along the side of the car substantially its entire length, means connecting the shoe and shaft, an operating lever disposed near each end of the car, and flexible means connecting the shaft with the two operating levers, said flexible means and operating levers being so arranged that movement of one of the operating levers to locking position will not move the other operating lever.

2. The combination with a car having 80 wheels thereon, of a brake mechanism for the car, said mechanism including a brake shoe movable vertically into and out of wheel engaging position, an operating lever adjacent each end of the car, means engaging said operating levers to hold them in the position to which they are moved, a shaft at each side of the car extending substantially the entire length thereof, cranks near the opposite ends of each shaft, cranks on each lever, and chains connecting each lever with the cranks on the shafts on each side of the car at their respective ends, and a crank on each shaft connected with the respective brake shoes, said levers and chains thus being so arranged as to enable the one operating handle to be moved to braking position after the other handle has been set to braking position, whereby movement of the operating lever at one end of the car to releasing position will not release the brakes unless the other also is in released position.

3. The combination with a car having 95 wheels thereon, of a braking mechanism therefor, said braking mechanism including a shoe at each side of the car movable into and out of wheel engaging position, a longitudinally extending shaft at each side of the car, a link and lever connecting the respective shoes with the respective side shafts, a transverse shaft extending across the car near one end thereof, a crank near each end of said transverse rod, a crank on each of said side shafts in juxtaposition to said cranks on the transverse rod, flexible means connecting said last mentioned cranks on the side shafts with those on the transverse rod, a lever for operating said transverse rod to apply and release the brakes, and means at the other end of the car including an operating lever and flexible connections for applying and releasing the brakes, said flexible connections enabling the brakes to be set at either or both ends of the car and being so arranged that when set from one end of the car, they may only be released at said end.

4. The combination with a mine car hav-

ing wheels, of a brake therefor including
brake shoes, operating mechanism for the
brake shoes, a lever near one end of the car
connected with said operating mechanism
movable in a longitudinal direction for ac-
tuating the brakes, and a second lever at
the other end of the car connected with said

actuating mechanism movable in a trans-
verse direction for actuating said brakes.

In testimony whereof we hereunto affix 10
our signatures.

JOHN A. HEBB.

WILLIAM J. McDADE.
